UNITED STATES PATENT OFFICE.

AMOS H. SMITH, OF NEW YORK, N. Y., ASSIGNOR TO AMERICAN BANK NOTE COMPANY, A CORPORATION OF NEW YORK.

PERFORATING-MACHINE.

1,120,753.

Specification of Letters Patent.

Patented Dec. 15, 1914.

Application filed November 29, 1913. Serial No. 803,674.

To all whom it may concern:

Be it known that I, AMOS H. SMITH, a citizen of the United States, residing in the borough of Bronx, in the city of New York, 5 county of Bronx, and State of New York, have invented certain new and useful Improvements in Perforating-Machines, of which the following is a specification, reference being had therein to the accompanying drawings, which form a part thereof.

My invention relates to perforating machines, and more particularly to a type thereof wherein the sheet to be perforated is fed to and delivered by the machine at 15 the same point, or what is commonly known as a backing out perforating machine.

The main object of the invention is to provide a machine of this character which is capable of being mechanically actuated, 20 as distinguished from the present type of hand operated machines.

A further object is to provide a machine wherein the perforating rollers will be rotated to a predetermined extent to secure the 25 desired length of a perforated line and will be automatically reversed or rotated in the opposite direction to accomplish the delivery of the sheet and avoid mutilation thereof through a loss of register of the punches 30 with the already formed perforations.

A still further object is to provide a machine of this type which may be so adjusted or set as to adapt it for making lines of perforations of varying lengths, the adjustment determining the extent of rotative 35 movement in one direction and the point of reversal of this movement.

A still further object is to provide a machine of this type wherein the perforating rollers will, after each actuation thereof, be brought to a complete rest at a point which will insure the perforating action thereof upon the following sheet under conditions 40 which will insure uniformity in the length 45 of the perforated lines of all sheets fed thereto. And a still further object is to provide a machine of this character wherein the paper sheets will be fed thereto through the perforating rollers by a mechanism controlled by and actuated in synchronism with 50 said perforating rollers.

The invention consists primarily in a perforating machine embodying therein a pair of perforating rollers, rotary main actuating 55 means, and operative connections be-

tween said rollers and said main actuating means whereby said rollers are rotated in opposite directions alternately with each full rotation of said actuating means; and in such other novel features of construction 60 and combination of parts as are hereinafter set forth and described, and more particularly pointed out in the claims hereto appended.

Referring to the drawings:—Figure 1 is 65 a side elevation of a machine embodying my invention; Fig. 2 is a rear elevation thereof; Fig. 3 is a detail cross sectional view of the perforating rollers and the feed rollers; and Figs. 4 and 5 are detail views 70 of the main actuating clutch mechanism.

Like letters refer to like parts throughout the several views.

In the embodiment of my invention shown in the drawings, *a* indicates the main 75 frame of the machine, in the top frame *b* of which are mounted the perforating rollers *c* and *d*, the first of which carries the punches *c'* and the other of which carries the die parts *d'*. These rollers are of the 80 ordinary and well known construction, and such as have heretofore been actuated by means of an ordinary hand crank. Adjacent to said pair of rollers is the feed shelf *e*, the detailed construction of which, in the 85 form of the invention shown in the drawings, will be more fully referred to hereinafter. The rollers *c* and *d* are geared together by means of the gears *c'* *d'*.

The perforating rollers, by my invention, 90 instead of being hand actuated, are operated under mechanical power such as the main actuating mechanism, comprising the crank wheel *f*, the driving wheel *g* and operative connections between said driving 95 wheel and said crank wheel, and said crank wheel and said rotary perforating rollers.

Inasmuch as in this type of machine, the sheets must be fed to the perforating rollers from the shelf *e* and delivered by said 100 rollers to said shelf, it is necessary to provide a structure wherein said rollers will be rotated in opposite directions alternately with each complete rotation of the crank wheel *f*. In the form of the invention illustrated, to secure this operative effect, I provide the journal of one of the perforating rollers, as *d*, with a gear wheel *h* in mesh with a segmental oscillatory rack *i*, mounted 105 adjacent thereto, which rack is reciprocated 110

by the crank wheel f through the connecting rod j . By this construction, not only am I enabled to secure the desired accurate reversing of the direction of rotation of the perforating rollers, but avoid likelihood of injury to the sheets of paper to be perforated by starting the feeding movement of the rollers from a condition of absolute rest, increasing the velocity thereof gradually 10 until the perforating work is well underway and gradually bringing the rollers to a dead stop prior to the reversal of the movement thereof, and accomplishing the delivery of the sheets by a sequence of similar movements.

To adapt the machine to work requiring perforated lines of varying lengths, I provide means whereby the effective throw of the oscillatory gear segment i may be varied, thus permitting a variance in the quantity of rotative movement of the rotary perforators with each complete rotation of the main actuating means. To secure this result, I provide the segment i with a radially extending elongated slot i' , and mount the crank pin j' , upon which the rod j is mounted, in this slot in such manner as to permit its adjustment lengthwise thereof. I also provide the crank wheel f with a radially extending elongated slot f' , in which the crank pin j^2 upon which the other end of the rod j is mounted, is adjustably mounted. By this construction, I am enabled to secure practically any desired quantity of 35 rotative movement of the perforating rollers $c d$, through a variance in the effective radii of the wheel f or segment i upon which the connecting rod j acts.

Mounted upon the feed shelf e are the rollers $h h'$, about which an endless flexible feeding sheet h^2 passes. The first named of these rollers, h , is mounted adjacent the perforating roller d , and is driven therefrom and in synchronism therewith by means of 40 the gear l and the idler gear m in mesh therewith and with the gear d^2 . Oppositely disposed to, and bearing upon, the feed roller h is a second roller n adapted to be frictionally driven. The roller n is mounted 45 in the pivoted arms n' , and means are provided, as the cams o , rotating in synchronism with the perforating rollers $c d$, for actuating the arms n' to raise the roller n prior to the initiation of the feeding movement 50 of the roller h upon the direct feed thereof, or of the backing out operation of the machine. These cams being mounted upon the shaft of the roller d , the opening and closing of the rollers is synchronized with the 55 operation of said perforating rollers.

When a machine of the character herein described is in use, the driving wheel g is continuously rotated, and inasmuch as the operative relation of the sheet to be perforated toward the perforating rollers, is

manually controlled, it is desirable to provide means, under the control of the operator, whereby after each complete cycle of operations, the perforating rollers will be capable of automatic disconnection from said driving wheel g . To secure this operative effect in the form of the invention shown, I mount upon the shaft f^2 of the crank wheel f , a drum p having a recess in the periphery thereof, in which is seated a spring pressed pawl p' , having a normal tendency to move outward radially of said drum. Loosely mounted upon said shaft f^2 in close proximity to the drum p , is the gear wheel q , undercut as shown in Fig. 4, the 80 drum p projecting into said undercut portion. Said gear q on the periphery of the undercut portion thereof, has a socket q' adapted to receive the pawl p' , and thus transmit motion from said gear q to the drum p and the shaft f^2 . The pawl p' is provided with a trip finger p^2 , projecting beyond the periphery of the gear q , by means of which the outward projection of the said pawl p' may be prevented.

Mounted in a fixed frame r , adjacent the drum p , is a contact pin s adapted to be normally projected into the path of the trip finger p^2 . Hence, under normal conditions, said pin will be in a position where it will prevent the pawl p' from moving outwardly, thus causing the gear q to run idly and transmit no movement to the perforating wheels. To cause the operation of the machine, I provide means as the bell crank lever t connected with the pin s and adapted to retract same out of the path of the trip finger p^2 , whereby said pin may be rendered inoperative to permit the pawl to move outwardly and transmit the desired power from the driving wheel g and its gear g' through said clutch mechanism to the crank wheel f and the perforating rollers. This bell crank lever is under the control of an ordinary foot treadle. By this mechanism, the release of the foot treadle will have the effect of disconnecting the main driving wheel from the crank wheel actuating means, but this disconnection will occur only upon the completion of any cycle of operations of the machine. Hence, the perforating rollers, when the machine is out of operation, will always come to rest at a certain point, and the machine must complete its full cycle of operations, or accomplish the delivery of the perforated sheet, before coming to rest.

The essential characteristics of the machine are the mechanical driving means for the perforating rollers, by which during a complete rotation or cycle of the main actuating means, a sheet will be fed, perforated and delivered with accuracy; and the operation of the perforating rollers in a manner to vary the speed thereof from a slow peripheral velocity in starting, to the 130

maximum speed while the perforating is going on, and a gradually reduced speed to the point of reversal of the perforators for the backing out operation.

5 In connection with the above, I employ means for varying the quantity of operative movement of the perforating rollers with a main actuating mechanism, the operations of which are uniform and constant. The 10 effective operation of the machine is increased by the particular feeding mechanism and the particular clutch mechanism heretofore described, which features, however, are of secondary importance in a machine of 15 this character.

The operation of the herein described perforating machine is substantially as follows:—When it is desired to start the machine, the treadle mechanism is actuated to 20 cause the bell crank lever *t* to actuate the contact pin *s* in a manner to draw it without the operative range of the trip finger *p*² of the pawl *p*'. The power from the main driving wheel *g* rotating the gear 25 wheel *q* will, as the said gear wheel is rotated, bring the socket *q*' thereof into operative relation to the pawl *p*', which moving outwardly, will enter said socket and cause said gear *q* to transmit movement 30 to the block *p* and to the crank wheel *f*. When the parts are at rest, the cams *o* will be in a position where they will raise the arms *n*' and the roller *n*, thus affording clearance between said feeding rollers to 35 assist the feeder in securing a timely and accurate feeding of each sheet. Prior to the setting of the clutch mechanism, a sheet of paper to be perforated is fed to a back gage upon the feeding shelf *e*, with the forward edge between the rollers *k* *n*, the sheet resting upon the belt *k*². When power is 40 applied to the crank wheel *f*, said wheel will, through the connecting rod *j*, impart an oscillatory movement to the segmental 45 rack *i*, which, being in mesh with the gear *h* upon one of the perforating rollers, will impart a partial rotation to said perforating rollers, the extent of which rotation may be less than, exactly, or greater than, a full 50 rotation thereof. The two rollers being geared together, will have simultaneous, equal movement. With the initiation of the rotary movement of the perforating rollers *c* *d*, the feed roller *k* will be turned by 55 means of the gears *l* *m*, the peripheral velocity thereof being the same as that of the perforating rollers so that the paper will be fed to said rollers at a speed which will minimize any tendency of the punches to 60 mutilate the paper.

When the machine is at rest, the connecting rod *j* is preferably upon a dead center, thus insuring a starting of the feeding movement and the action of the perforators, 65 at a low speed, bringing the speed up to

maximum midway between centers, and gradually slowing the movement down so that at the end of the effective operative movement of the perforators, the connecting rod *j* will come to rest upon the opposite 70 center, preparatory to a reversal of the oscillatory movement of the segmental *i* to reverse the direction of rotation of the perforators and deliver the sheet by what is known as a backing out operation. This reverse rotation will have a variable speed in the same manner as in perforating. In backing out, not only is the operation of the perforating rollers reversed, but the operation of the feeding mechanism is also reversed, and all 75 80 mechanisms of the machine are reversed, excepting the main actuating mechanism, including the crank wheel *f*, which always rotates in the same direction in other words as uni-directional rotary movement. 85

If it be desired to make the machine inoperative, it is merely necessary to release the treadle mechanism, or reverse the operation thereof, thus projecting the contact pin *s* within the path of the trip finger *p*² so that 90 as said trip finger comes into engagement with said pin, it will be retracted within the recess in the drum *p* and thus disconnect said drum from the gear *q* and permit said gear to run idly. The advantage of this 95 operation is that whatever the position of parts when the contact pin *s* is set to throw the machine out of operation, the machine will complete its cycle of operations before it stops, and when at rest, the different 100 mechanisms will always occupy a certain definite position. Furthermore, if desired, the treadle may be actuated each time a sheet is perforated, so as to permit the operator to time the feeding movement with 105 the operative movement of the machine.

With each actuation of the machine, a line of perforations of the desired length will be made, and as a sequence of disks carrying punches and dies usually makes up the 110 perforating rollers, a plurality of such lines of perforations will be made simultaneously.

By adjusting the crank pin *g*' in the slot *z*', or the crank pin *j*' in the slot *f*', or by adjusting either or both of said crank pins, 115 the operative throw of the connecting rod *j* upon the segmental rack *i* may be controlled in a manner to accurately determine the length of the line of perforations to be made by the perforating rollers *c* *d*, or in other 120 words, the operative effect of the segmental rack *i* upon said perforators may be controlled through the radial adjustment of the points of connection of the connecting rod *j* with said segmental rack, or with 125 the crank wheel *f*. By this construction the same machine may be adjusted for making different lengths of perforated lines.

To adapt the feeding mechanism to such variances in the quantity of rotative move- 130

ment of the perforating rollers, the cams *o* are adjusted circumferentially of the shaft of the perforating roller *d*, so that when the connecting rod *j* imparts initial movement to the rack *i*, said cams will always be operative to raise the feed roller *n* out of the operative relation to the feed roller *k*. A machine of this type is adapted primarily to form a line of perforations extending along only a portion of the length of a sheet of paper, and the adjustment for controlling the length of the lines of perforations formed, is important in this type of machine, while having no utility in connection with a machine in which perforations along the entire sheet are to be formed.

The backing out operation also is applicable only to a type of machine wherein the line of perforations does not extend for the entire length of the sheet being perforated, it being necessary, in delivering the sheet, to have each of the punches enter the perforation made thereby during the direct feeding movement of the sheet.

While the main actuating mechanism, including the crank wheel *f*, rotates continuously in one direction, the connecting rod *j* will impart an oscillatory movement to the segmental gear *i*, and thus rotate the perforating rollers in opposite directions alternately, with each full rotation of said main actuating means.

By the mechanism herein described, I am enabled to produce a machine which will operate at uniform speeds during any cycle of operations thereof, wherein the succeeding sequence of operations will be accurately timed and wherein succeeding sheets of paper may have perforated lines formed therein of uniform length, without likelihood of the overrunning of the perforators, or mutilation of the sheet thereby.

The timing of the feeding mechanism to and in accordance with the operative interval of the perforating rollers, prevents any drag upon the paper which might tend toward a tearing thereof, and by reversing the rotation of the feeding mechanism during the backing out operation of the perforating rollers, I assist in the delivery of the sheet.

It is not my intention to limit myself to the precise details of construction shown in the accompanying drawings, it being apparent that such may be varied without departing from the spirit and scope of the invention.

Having described my invention, what I claim as new, and desire to have protected by Letters Patent, is:—

1. A perforating machine embodying therein a pair of perforating rollers, rotary main actuating means, and operative connections between said rollers and said main actuating means whereby said rollers are ro-

tated in opposite directions, alternately, with each full rotation of said actuating means.

2. A perforating machine embodying therein a pair of perforating rollers, rotary main actuating means, operative connections between said rollers and said main actuating means whereby said rollers are rotated in opposite directions, alternately, with each full rotation of said actuating means, and means whereby said main actuating means may be made inoperative to cause said operative connections to stop and start at a predetermined point.

3. A perforating machine embodying therein a pair of perforating rollers, a main actuating mechanism, and operative connections between said rollers and said main actuating mechanism, whereby said rollers are rotated in opposite directions, alternately, said connections including therein means whereby said rollers may be started at slow speed, the speed thereof gradually increased, and then gradually reduced to a full stop prior to the reversal of the direction of rotation thereof.

4. A perforating machine embodying therein a pair of perforating rollers, rotary main actuating means, operative connections between said rollers and said main actuating means whereby said rollers are rotated in opposite directions, alternately, with each full rotation of said actuating means, and a feeding mechanism adapted to deliver sheets to be perforated to said rollers, at a speed substantially equaling the peripheral velocity of said rollers.

5. A perforating machine embodying therein a pair of perforating rollers, a main actuating mechanism, operative connections between said rollers and said main actuating mechanism, whereby said rollers are rotated in opposite directions, alternately, said connections including therein means whereby said rollers may be started at slow speed, the speed thereof gradually increased, and then gradually reduced to a full stop prior to the reversal of the direction of rotation thereof, and a feeding mechanism adapted to deliver sheets to be perforated to said rollers, at a speed substantially equaling the peripheral velocity of said rollers.

6. A perforating machine embodying therein a pair of perforating rollers, rotary main actuating means, operative connections between said rollers and said main actuating means whereby said rollers are rotated in opposite directions, alternately, with each full rotation of said actuating means, and means whereby said connections may be adjusted to vary the quantity of rotative movement of said rollers with each rotation of said main actuating means.

7. A perforating machine embodying therein a pair of perforating rollers, a main actuating mechanism, operative connections

between said rollers and said main actuating mechanism, whereby said rollers are rotated in opposite directions, alternately, said connections including therein means whereby 5 said rollers may be started at low speed, the speed thereof gradually increased, and then gradually reduced to a full stop prior to the reversal of the direction of rotation thereof, and means whereby said connections may be 10 adjusted to vary the quantity of rotative movement of said rollers without varying the mode of operation of said main actuating mechanism.

8. A perforating machine embodying 15 therein a pair of perforating rollers, a rotary member, an oscillatory rack, a gear carried by one of said perforating rollers in mesh with said rack, a connecting rod between said rotary member and said oscillatory rack, whereby the rotary movement of 20 said rotary member imparts a reciprocatory movement to said rack to rotate said rollers in opposite directions, alternately, with each full rotation of said rotary member, and 25 means imparting continuous, unidirectional rotary movement to said rotary member.

9. A perforating machine embodying 30 therein a pair of perforating rollers, a rotary member, an oscillatory rack, a gear carried by one of said perforating rollers in mesh with said rack, a connecting rod between said rotary member and said oscillatory rack, whereby the rotary movement of 35 said rotary member imparts a reciprocatory movement to said rack to rotate said rollers in opposite directions, alternately, with each full rotation of said rotary member, means imparting continuous, unidirectional rotary movement to said rotary member, and means 40 whereby said rotary member may be disconnected from said last named means to make said rack inoperative or cause said perforating rollers to stop and start at a predetermined point.

45 10. A perforating machine embodying 45 therein a pair of perforating rollers, a rotary member, an oscillatory rack, a gear carried by one of said perforating rollers in mesh with said rack, a connecting rod between said rotary member and said oscillatory rack, whereby the rotary movement of 50 said rotary member imparts a reciprocatory movement to said rack to rotate said rollers in opposite directions, alternately, with each 55 full rotation of said rotary member, means imparting continuous, unidirectional rotary movement to said rotary member, and a feeding mechanism adapted to deliver sheets to be perforated to said rollers, at a speed 60 substantially equaling the peripheral velocity of said rollers.

11. A perforating machine embodying 65 therein a pair of perforating rollers, rotary main actuating means, operative connections between said rollers and said main actuating

means whereby said rollers are rotated in opposite directions, alternately, with each full rotation of said actuating means, and a feeding mechanism embodying therein parallel rollers, a feed sheet or belt passing 70 about same, means whereby one of said rollers is driven from and at the same speed as said perforating rollers, whereby sheets will be delivered to or from said perforating rollers at a speed substantially equaling the 75 peripheral velocity of said perforating rollers.

12. A perforating machine embodying 80 therein a pair of perforating rollers, a rotary member, an oscillatory rack, a gear carried by one of said perforating rollers in mesh with said rack, a connecting rod between said rotary member and said oscillatory rack, whereby the rotary movement of 85 said rotary member imparts a reciprocatory movement to said rack to rotate said rollers in opposite directions, alternately, with each full rotation of said rotary member, means imparting continuous, unidirectional rotary movement to said rotary member, and a 90 feeding mechanism embodying therein parallel rollers, a feed sheet or belt passing about same, means whereby one of said rollers is driven from and at the same speed as said perforating rollers, whereby sheets will 95 be delivered to or from said perforating rollers at a speed substantially equaling the peripheral velocity of said perforating rollers.

13. A perforating machine embodying 100 therein a pair of perforating rollers, rotary main actuating means, operative connections between said rollers and said main actuating means whereby said rollers are rotated in opposite directions, alternately, with each 105 full rotation of said actuating means, and a feeding mechanism embodying therein parallel rollers, a feed sheet or belt passing about same, means whereby one of said rollers is driven from and at the same speed as 110 said perforating rollers, whereby sheets will be delivered to or from said perforating rollers at a speed substantially equaling the peripheral velocity of said perforating rollers, a vertically movable feeding roller bearing upon one of said belt or sheet rollers, and means carried by said perforating rollers whereby said last named roller will be raised at a predetermined point in the rotation of said perforating rollers. 115

14. A perforating machine embodying 120 therein a pair of perforating rollers, a rotary member, an oscillatory rack, a gear carried by one of said perforating rollers in mesh with said rack, a connecting rod between said rotary member and said oscillatory rack, whereby the rotary movement of 125 said rotary member imparts a reciprocatory movement to said rack to rotate said rollers in opposite directions, alternately, with each 130

full rotation of said rotary member, means whereby said connecting rod may be adjusted radially of said rack to vary the quantity of its reciprocatory movement, and means imparting continuous, unidirectional rotary movement to said rotary member.

15. A perforating machine embodying therein a pair of perforating rollers, a rotary member, an oscillatory rack, a gear carried by one of said perforating rollers in mesh with said rack, a connecting rod between said rotary member and said oscillatory rack, whereby the rotary movement of said rotary member imparts a reciprocatory movement to said rack to rotate said rollers in opposite directions, alternately, with each full rotation of said rotary member, means whereby said connecting rod may be adjusted radially of said rotary member to 20 vary the effective operative movement thereof, and means imparting continuous, unidirectional rotary movement to said rotary member.

16. A perforating machine embodying therein a pair of perforating rollers, a ro-

10 tary member, an oscillatory rack, a gear carried by one of said perforating rollers in mesh with said rack, a connecting rod between said rotary member and said oscillatory rack, whereby the rotary movement of 15 said rotary member imparts a reciprocatory movement to said rack to rotate said rollers in opposite directions, alternately, with each full rotation of said rotary member, means whereby said connecting rod may be adjusted radially of said rotary member to 20 vary the effective operative movement thereof, and means imparting continuous, unidirectional rotary movement to said rotary member.

25 In witness whereof, I have hereunto affixed my signature, in the presence of two subscribing witnesses, this 24th day of November, 1913.

AMOS H. SMITH.
